UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM.

Application filed May 8, 1928. Serial No. 276,046.

This invention relates to warp stop mechanisms for looms and is more particularly directed to warp stop mechanisms of the transversely movable toothed detector bar type and 5 means for supporting and bracing the transversely extending elements thereof.

In warp stop mechanisms of the above general type there are now generally employed a fixed toothed detector bar and a transversely 10 movable toothed detector bar which are passed through drop wires normally supported by the warp threads during weaving. It is desirable that the transversely extending 15 toothed detector bars shall be of light construction and readily removable from the loom to permit change of warp. Where the detector bars are of considerable length and are of light construction, they are liable to be bent or deflected from their straight transversely extending position during the weaving 20 operation, and one of the objects of the present invention is to provide a bridge construction to maintain the toothed detector bars from distortion during weaving and at 25 the same time to permit unobstructed removal of such transversely extending toothed detector bars from the loom when the warp is to be changed.

In accordance with the present invention, 30 a bridge member is provided having open sockets along its upper edge in which the toothed detector bars may be supported below their upper toothed edges and from which, without manipulation of any part connected 35 to the bridge member, their removal may be effected without disturbance of the bridge member or parts associated therewith.

The present invention is an improvement upon the warp stop mechanism shown and 40 described in the Davis and Johnson Patent, No. 1,538,625, dated May 19, 1925, and the novel features thereof will best be made clear from the following description and the accompanying drawings of one good form 45 thereof.

In the drawings:

Fig. 1 is a side elevation of a warp stop mechanism of the general type shown in the Davis and Johnson Patent, only part of the 50 warp stop motion being illustrated;

Fig. 2 is an enlarged section on the line 2—2 of Fig. 1;

Fig. 3 is an enlarged elevation in end view 55 of the bridge member and its associated parts; and

Fig. 4 is a plan view showing more particularly the bridge member in association with the transversely movable toothed detector bars.

Mounted at each side of the loom is a 60 bracket or support 1, in the upper edge portion 2 of which the fixed detector bars 3 are mounted. The fixed detector bars 3 are provided with guideways extending longitudinally thereof for the reception of the transversely movable detector bars 4 having teeth 5 extending from their upper edges, and connected with each of the transversely movable detector bars is a link 6 pivotally connected at 7 to an associated actuator 8. The actuators 8, of which there may be any suitable 70 number in accordance with the number of banks of drop wires and detector bars employed, are mounted upon a rocker 9 by means of pins or supports 10 which engage sockets 75 in the associated rocker, and a spring 11 normally holds the actuators and rockers in operative relation, as indicated in Fig. 1. The rockers 9 are mounted upon a rock shaft 12 which is given rocking movement by an arm 80 13 actuated from a going part of the loom, as, for instance, the lower or cam shaft, by an arm 14.

Each of the actuators 8 is provided with a stop finger 15 which rests upon a pivotally mounted arm 16. Engaged with the under portion of the arm 16 is a plunger 18 associated with a flexible sheathed wire 19 through which loom stoppage may be effected upon longitudinal movement of the sheathed wire. 90 These parts and the drop wires 20 mounted upon the detector bars by means of slots in the upper portions of the drop wires, as indicated in Fig. 1, may all be of the same general type or character as more fully described 95 in the Davis and Johnson patent.

Extending between the brackets 1 at each side of the loom are the drop wire separator bars 21, and such separator bars are properly engaged with the side brackets 1.

As hereinbefore indicated, it is desirable at times to remove the fixed and movable toothed detector bars and the drop wires associated therewith, a condition which arises when the warp in the loom is to be changed, and to 105 effect this result of the unobstructed removal of the toothed detector bars, while at the same time supporting and bracing said detector bars between their end portions, the present invention provides a brace or bridge mem- 110

ber 22 having open slots or sockets 23 in its upper edge, so that the toothed portions of the detector bars are above the upper edge of the bridge or bracing member 22, as more clearly indicated in Fig. 2.

The bridge member 22 is likewise provided with open sockets 24 along its lower edge which embrace the drop wire separator bars 21, as more clearly indicated in Fig. 2, and a single clamping member is provided below the separator bars for holding the bridge member 22 in its associated relation with the transversely extending toothed detector bars, so that the latter and their series of drop wires may be readily removed without obstruction and without manipulation of any part of the bridge member.

The clamping member for effecting the above results consists of an arm 25 pivotally mounted at 26 to the downwardly extending portion of the bridge member 22, and such clamping member 25 is provided with open sockets 27 and 28 into which the lower edge portions of the end separator members 21 may be engaged. The sockets 27 and 28 in the bridge member are of such depth that when the clamp 25 is in its clamping position, as indicated by full lines in Fig. 2, the lower edge portions 29 of the end separator bars are clamped therein, thereby maintaining the clamping member 25 in position relative to the transversely extending members of the warp stop mechanism, and effectively preventing any lateral or bending movement of the end separating members.

Pivottally connected to the clamping member 25 at 30 is the securing bolt 31, and as a further means of aligning the bridge member 22 in associated relation with the transversely movable detector bars and separator bars, the bridge member 22 is provided with laterally extending lugs 32 in which the bolt 31 rests when in operative position, as indicated in Fig. 2.

Above the lugs 32 the bridge member 22 is provided with the outwardly extending lugs 33 which embrace the upper end of the bolt 31, and threaded to the upper end of the bolt is the winged nut 34, the construction being such that when the winged nut 34 is screwed to its clamping position, the lower clamping member 25 will securely hold the bridge member and associated parts in proper relation for effecting its desired function, and the lower lugs 32 act to align the bridge member 22 in transverse relation to the detector bars and separator bars.

The inner edge portions 35 of the lower lugs 32 bear upon the side of the end separator bar 21 and similarly at the opposite side of the bridge the laterally extending lugs 36 bear upon the outer surface of the opposite separator bars 21, thereby co-acting with the lugs 32 and clamping bolt to maintain the bridge member in proper transverse posi-

tion relative to the detector and separator bars.

From the construction described as one good practical embodiment of the present invention, it will be apparent that a simple and effective means is provided for supporting and bracing the transversely movable and fixed toothed detector bars which may be readily removed from the warp stop mechanism along with the drop wires without obstruction of any overlying part, so that without manipulating the parts of the bridge member, the warp of the loom may be readily taken therefrom along with the movable and fixed detector bars during the change of warp, and it will also be apparent that the transverse alignment of the bridge member is insured by the lugs 32 and opposite projections 35 and 36, so that when the bridge member is in place it will be aligned accurately in transverse relation to the fixed and movable detector bars and separator bars.

The present invention provides a simple and effective means for bracing and supporting the transversely extending fixed and movable detector bars for unobstructed removal from the loom and for supporting and bracing the separator bars for the drop wires.

What is claimed is:

1. In a warp stop mechanism for looms, the combination of transversely movable toothed detector bars, fixed detector bars supporting the transversely movable detector bars, a plurality of drop wires through which the detector bars pass, spacing bars for the drop wires, a bridge member having open sockets formed in its upper edge to receive and support the detector bars and constructed to hold the bars against twisting or turning movement while permitting unobstructed removal of the detector bars therefrom, and open sockets in its lower edge to receive the spacing bars, and a single clamping member having open sockets for engaging the end spacing bars, and means for securing the clamping member in clamping position.

2. In a warp stop mechanism for looms, the combination of transversely movable toothed detector bars, fixed detector bars having grooves for holding and guiding the movable detector bars, a plurality of drop wires strung upon the detector bars, a bridge member having open sockets to receive and support the detector bars and constructed to hold the bars from twisting or turning while permitting unobstructed removal of the detector bars and drop wires, bolt receiving lugs extending from the upper and the lower part of the bridge member to hold the securing bolt from moving laterally, spacing bars, a single clamping member below the spacing bars, and a securing bolt engaging the lugs of the bridge member for securing the bridge member and clamping member in place.

3. In a warp stop mechanism for looms, the

- combination of transversely movable toothed detector bars, fixed detector guide bars, a series of drop wires through which the two bars extend, drop wire separator bars, a bridge member having open slots in its upper edge for supporting and bracing the detector bars below their toothed edges and adapted to engage the opposite sides of the detector bars to prevent them from twisting or turning while permitting unobstructed upward removal of said bars and drop wires, and also having slots in its lower edge for supporting and bracing the separator bars, a single clamp member for holding the bridge member clamped to the separator bars and having an open socket at each end for embracing the end members of the separator bars, and a screw bolt secured to the single clamp member and engaging the bridge member.
4. In a warp stop mechanism for looms, the combination of transversely movable toothed detector bars, fixed detector bars having grooves for holding and guiding the movable detector bars, a plurality of drop wires strung upon the detector bars, a bridge member having open sockets to snugly receive and support the detector bars and permitting unobstructed removal of the detector bars and drop wires, bolt receiving projections extending from an end of the bridge member and adapted to hold the bolt from moving laterally of the bridge member, spacing bars, a single clamping member below the spacing bars and adapted to exert a gripping action on said bars, and a securing bolt engaging said projections for securing the bridge member and clamping member in place.
5. In a warp stop mechanism for looms, the combination of transversely movable toothed detector bars, fixed detector bars having grooves for holding and guiding the movable detector bars, a plurality of drop wires strung upon the detector bars, a bridge member having open sockets to snugly receive and support the detector bars and permitting unobstructed removal of the detector bars and drop wires, bolt receiving projections extending from an end of the bridge member and adapted to hold the bolt from moving laterally of the bridge member, spacing bars, a single clamping member below the spacing bars and adapted to exert a gripping action on said bars, and a securing bolt engaging said projections for securing the bridge member and clamping member in place.

member for holding the bridge member clamped to the separator bars and having an open socket at each end for embracing the end members of the separator bars, a screw bolt secured to the single clamp member and engaging the bridge member, and aligning lugs extending laterally from each end portion of the bridge member for resting against the end separator bars to insure proper alignment of the bridge member.

5. In a warp stop mechanism for looms, the combination of transversely movable detector bars, fixed detector bars having grooves for holding and guiding the movable detector bars, a plurality of drop wires strung upon the detector bars, a bridge member having open sockets to snugly receive and support the detector bars and permitting unobstructed removal of the detector bars and drop wires, bolt receiving projections extending from an end of the bridge member and adapted to hold the bolt from moving laterally of the bridge member, spacing bars, a single clamping member below the spacing bars and adapted to exert a gripping action on said bars, and a securing bolt engaging said projections for securing the bridge member and clamping member in place.

In testimony whereof, I have signed my name to this specification.

CARL D. BROWN.
